UNITED STATES PATENT OFFICE.

JOSEPH S. ELLIOTT, OF PHILADELPHIA, PENNSYLVANIA.

IMPROVEMENT IN GAS-METERS.

Specification forming part of Letters Patent No. 39,904, dated September 15, 1863.

To all whom it may concern:

Be it known that I, JOSEPH S. ELLIOTT, of the city of Philadelphia, in the State of Pennsylvania, have invented a new and useful Improvement in Gas-Meters; and I do hereby declare that the following is a full, clear, and exact description of the construction and operation of the same, reference being had to the accompanying drawings, making a part of this specification, in which—

Figure 1 is a plan view of the register of a gas-meter having its back plate removed and showing my improvement applied thereto and Fig. 2 an edge view of the same.

Like letters and numerals indicate the same parts when in both figures.

Letters Patent bearing date the 17th day of September, 1861, were granted to me for a certain improvement in the registers of gas-meters, and the present invention has relation to the same part of the apparatus. In the use of the registers manufactured under the said patent it has been found, although perfect in their operation under the usual speed at which meters are run, that when run at the high speeds sometimes required, the drivers are liable to become interlocked with the driven wheels at the time the recesses in the peripheries of the former are receiving or passing the stop-teeth of the latter, and to remedy this defect is one of the objects of my present invention.

It consists, substantially as hereinafter described and specified, in stopping or holding the driven wheels by means of levers, each arranged to vibrate between the periphery of the driver and the stop-teeth of the driven of each pair of wheels only at the time the former is moving the latter.

In the drawings, A A' A² A³ A⁴ A⁵ are the index-wheels, and B B' B² B³ B⁴ the levers which connect the said wheels together in pairs. The first wheel, A, has in this instance two driving-teeth, 1 1, while each of the four succeeding wheels, A' A² A³ A⁴, has only one driving-tooth, 2, as indicated by dotted lines in Fig. 1. The sixth wheel, A⁵, not being used as a driver, has not any driving-tooth. On the opposite side of each of the disks of the wheels provided with a single driving-tooth, 2, there are ten teeth, 3 3, and on the same side of the disk of the last or sixth wheel, A⁵, there are also provided ten teeth, in both cases

to correspond with the usual ten numerals of their respective dial-plates D D. The teeth are all in the form of short cylinders rising perpendicularly from the planes of the disks, and also arranged in the relative positions to each other and to the centers of the disks. (Seen in the drawings.) The teeth-disk of the first wheel, A, has two curved recesses, 4 4, in its periphery, while each of the four succeeding wheels, A' A² A³ A⁴, has but one recess, 5. The levers B have their arms made of equal lengths, and are fixed to respective shafts, which are supported by journals or pivots between the plates E E, in positions parallel to the shafts of the wheels A, as seen in the drawings. They are each formed out of sheet-brass in the curved form seen in the drawings, fixed to their shafts, and bent so that while one end is in contact with the periphery of a driver the other end will be in loose contact with or between two of the stop-teeth 3 of the driven wheel of its pair, and so arranged also that when one end of the lever is being raised and passed by the stop-teeth of the driven wheel, the other end will be permitted to freely enter the curved recess 4 in the periphery of the driver, the driving-teeth being placed so as to engage the stop-teeth and thus move the driven wheel as the curved recess of the former passes under the end of the lever with which it is connected. The teeth are cast smooth with the disk and shaft in a suitable mold, and the peripheries of the disks afterward turned off smooth in a lathe. The curved ends of the levers B are also dressed smooth on their edges.

It will be readily seen that in operation the levers B will stop or hold the driven wheels stationary while the drivers are being rotated, until the curved recesses 4 of the latter arrive under the respective ends of the levers and the driving-teeth 2 engage the stop-teeth 3 and thus move the driven wheel—its stop-teeth now being permitted to pass freely under the respective ends of the levers; and that the rubbing surfaces being of different metals and smooth, and the levers free in their motions, the friction to be overcome is necessarily very slight, and that the drivers cannot at any time become interlocked with the driven wheels. It will also be readily seen that by casting the shafts, disks, and teeth of the wheels each in one solid piece at one op-

eration, as described, must reduce the cost and insure greater uniformity in their construction.

Having thus fully described my improvement in gas-meters and pointed out its utility, what I claim as new therein of my invention, and desire to secure by Letters Patent, is—

Producing the stop-motions in the registers of gas-meters by means of the levers B, or

their equivalents, arranged to operate in combination with the recesses and teeth of the wheels A, substantially in the manner described and set forth, for the purpose specified.

J. S. ELLIOTT.
